US00D758280S

(12) **United States Design Patent**
Hurd

(10) **Patent No.:** **US D758,280 S**
(45) **Date of Patent:** **** Jun. 7, 2016**

(54) **OAR**

(71) Applicant: **Russell John Hurd**, Fort Pierce, FL (US)

(72) Inventor: **Russell John Hurd**, Fort Pierce, FL (US)

(73) Assignee: **Russell J. Hurd**, Fort Pierce, FL (US)

(**) Term: **14 Years**

(21) Appl. No.: **29/474,965**

(22) Filed: **Apr. 6, 2015**

(51) LOC (10) Cl. **12-06**

(52) U.S. Cl.

USPC **D12/215**

(58) **Field of Classification Search**

USPC D12/215; D8/10

CPC B63H 16/04; B63H 16/046

See application file for complete search history.
